UNITED STATES PATENT OFFICE.

ANTON CONGELLIER, OF MILWAUKEE, WISCONSIN.

INTERNAL-COMBUSTION ENGINE.

Application filed July 26, 1924. Serial No. 728,459.

This invention relates to internal combustion engines.

In internal combustion engines as heretofore constructed, the total amount of charge that can be drawn into a cylinder is determined by the volume of the cylinder. There is, therefore, an inherent limitation of the output of any given engine. Further than this low grades of fuel cannot be successfully employed with the usual types of engines.

This invention is designed to overcome the above noted defects, and objects of such invention are to provide an internal combustion engine in which a greater charge can be forced into the cylinders than has been heretofore possible, in which a cheap grade of fuel may be employed, and in which an increased output may be secured.

An embodiment of the invention is shown in the accompanying drawings, in which:—

Figure 1 is a vertical sectional view through the engine.

Figure 2 is a transverse sectional view on the line 2—2 of Figure 1.

Figure 3 is a horizontal sectional view on the line 3—3 of Figure 2.

Figure 4 is an end view taken from the left hand side of Figure 1.

In the drawings a pair of working cylinders have been shown although it is to be understood that any number of cylinders may be employed. These working cylinders 1 are provided with the usual type of pistons 2 which are operatively connected with the crank shaft, not shown.

The cylinders are equipped with inlet and outlet passages or ducts 3 and 4 (see Figure 2) controlled by valves in the usual manner, so as to provide a four cycle multi-cylinder engine, the valves having been omitted for the sake of clearness.

The cylinder head is extended upwardly and is provided with a plurality of auxiliary cylinders 5 within which auxiliary pistons 6 operate. These pistons are connected by means of links 7 with cranks 8 formed on an auxiliary driven shaft 9, such shaft being operatively coupled by means of gearings such as shown at 10 with the engine shaft.

It is to be noted that the auxiliary cylinders 5 are spaced upwardly from the main working cylinders 1, and a storage compartment or chamber 11 is provided intermediate each pair of auxiliary and working cylin-

ders. This storage reservoir communicates both with the main cylinder and with the auxiliary cylinder by means of ducts 12 and 13 respectively. Rotary valves 14 and 15 control these ducts and open and close them in a periodic manner hereinafter described. The auxiliary cylinders also are provided with ducts 16 which communicate with fuel inlet passages 17, the communication being controlled by valves 18, as may be seen from Figure 2.

The valves 14, 15 and 18 are of the rotary type, as may be seen from Figures 1, 2 and 3. They are preferably elongated cylindrical members provided with channels 19 cut through appropriate sides, as shown in Figure 3, and adapted to furnish passage ways communicating with the respective ducts in a well known manner. These rotary valves are also provided with hollow portions 20 into which a plurality of small holes 21 open. It is to be noted from reference to Figure 3 that these hollow portions are arranged adjacent recesses 22 formed in the cylinder block. It is intended that the rotary valves shall be oiled through this medium, that is to say, oil may be furnished by means of the cavities 22 and will pass through the apertures 21 into the enlarged hollow portion 20 of the rotary valve, thus facilitating their adequate oiling.

These rotary valves are each provided with gears operatively connecting them with the driven crank shaft 9, as shown in Figures 3 and 4. A gear 23 and a similar gear 24 are provided for the valves 15 and 18 and are connected by means of an idler 25 with a gear 26 carried by the auxiliary crank shaft 9. These gears are all of the same size and the gearing through which the crank shaft 9 is connected with the engine shaft is such as to drive the auxiliary crank shaft at the same speed as the engine shaft thus in turn driving the valves 15 and 18 at the same speed as the engine shaft. The valve 14 is provided with a gear 27 which meshes with a pinion 28 rigidly associated with one of the gears 23 or 24, as shown in Figure 4. The ratio of the pinion 28 and the gear 27 is such that the valve 14 is driven at one quarter engine speed.

The operation of the apparatus is as follows:—Assuming that one of the main pistons 2 is making a working stroke, the corresponding auxiliary piston 6 is then rising,

and through the medium of the valve 18 is drawing a fresh charge into the cylinder 5. The working piston 2 descends through its entire working stroke while the piston 6 is rising. Thereafter, the usual exhaust valve controlling the port of the main cylinder opens and the main working piston ascends driving out the burnt gases. At the same time, the corresponding auxiliary piston 6 descends and compresses its charge, communication with the inlet 17 being cut off by the valve 18 and communicating with the storage chamber 11 being established by the valve 15. This charge is forced into the storage compartment 11 under pressure and the intake of the main cylinder begins. The auxiliary cylinder is also drawing in a fresh charge of mixture while the main piston is descending. Thereafter, the main piston starts upward and compressing its normal charge. An instant after the passage at dead center, the valve 14 opens and the compressed charge stored in the compartment 11 is forced into the main cylinder. Also the auxiliary piston is descending and forces an additional supply of mixture through the chamber 11 and into the main cylinder. The valve 14 closes and the main piston completes its compression. The main cylinder charge is then exploded and the same cycle of operations is repeated.

It will be seen therefore, that means have been provided for augmenting the regular or normal charge drawn into a working cylinder, and that by this means an additional or auxiliary charge is forced into the main cylinder.

It will be seen, therefore, that any amount of charge may be forced into the main cylinder and that the output of the engine can be increased.

It may be found desirable under certain conditions to supply air to the intake 17 of the auxiliary cylinder and to force this air into the working cylinder, as described, thus raising the compression and increas-

ing the supply of air in the main cylinder. This procedure will be found highly desirable when a very low grade of fuel is being used.

It will be seen, therefore, that an internal combustion engine has been provided which has an output considerably in excess of that supplied by a similar engine under normal conditions, which may be operated to secure any desired supply of mixture for the main cylinder and any desired compression. Obviously the proportioning of the stroke and bore of the main and auxiliary cylinder will be covered by the amount of compression desired and the amount of volumetric displacement.

Although the invention has been described in considerable detail, it is to be understood that the invention may be variously embodied and is, therefore, to be limited only as claimed.

I claim:

An internal combustion engine comprising a main cylinder, an auxiliary cylinder, and a storage compartment between said cylinders, a main piston within said main cylinder, an auxiliary piston within said auxiliary cylinder, means for reciprocating said auxiliary piston a plurality of times for each stroke of said main piston, a rotary inlet valve controlling the admission of charge to said auxiliary cylinder, a rotary valve controlling discharge of the compressed charge from said auxiliary cylinder to said storage compartment, and a rotary discharge valve controlling discharge of the compressed charge from the storage compartment to said main cylinder, said last mentioned valve operating at a lower speed of rotation than said first mentioned valves.

In testimony that I claim the foregoing I have hereunto set my hand at Milwaukee, in the county of Milwaukee and State of Wisconsin.

ANTON CONGELLIER.
